DROP HAMMER AND CARRIAGE THEREFOR

Evan E. Dorkins, Ottawa, Kans., assignor to
Ottawa Steel Products, Inc., Ottawa, Kans., a
corporation of Kansas

Application January 16, 1950, Serial No. 138,811

5 Claims. (Cl. 262—13)

This invention relates to drop hammers and carriages therefor and more particularly to a portable hydraulically operated drop hammer on a carriage adapted to be towed or otherwise moved to places of use for driving and/or pulling posts and performing other work such as breaking, cutting or otherwise hammering and/or tamping pavement, soil and the like.

The objects of the invention are to provide a self-contained, portable unit including a carriage, power driven hydraulic system and an hydraulically operated drop hammer mechanism adjustably mounted on the carriage for vertical operation of the hammer when the carriage is on uneven or sloping surfaces; to provide a portable, hydraulically operated drop hammer mechanism on a carriage adapted to perform a large variety of functions both when stationary and when towed or otherwise moved over a surface as in road or right of way repair and maintenance; to provide an hydraulically operated drop hammer mechanism mounted on a suitable carriage in such a manner as to be tilted in any direction from a relatively vertical position and operated in said tilted position; to provide hydraulic means for raising an impact member or hammer as desired up to the upper limit of its motion and dropping the same by release of the hydraulic fluid; to provide hydraulic mechanism having control of a drop hammer at all times to permit substantially free falling of the hammer; to provide a drop hammer trackway mounting adapted for folding said trackway relative to a carriage for travel to locations of work; to provide for controlling operation of the hydraulically operated drop hammer from the driving seat of a towing vehicle; to provide a drop hammer structure and adapter for attaching various tools such as concrete breakers, chisels and tamping heads thereto; to provide a multipurpose hydraulically operated drop hammer and carriage therefor that is light in weight and easily maneuvered, placed in position and operated by one man; and to provide apparatus of this character that is economical to manufacture, sturdy in construction and efficient in operation to give either fast or slow and light or hard smashing blows with substantially no shock to the apparatus or operator.

In accomplishing these and other objects of the present invention, I have provided improved details of structure, the preferred forms of which are illustrated in the accompanying drawings, wherein:

Fig. 1 is a perspective view of the hydraulically operated drop hammer mounted on a carriage therefor.

Fig. 2 is a plan view of the carriage, the hammer and trackway therefor being shown in section to illustrate the structure thereof.

Fig. 3 is an end elevation of the hammer and carriage therefor with a tamper attachment, portions being broken away to better illustrate the structure thereof.

Fig. 4 is a partial elevation of the carriage and hammer trackways illustrating the tilting mechanism and trackways in partially folded condition.

Fig. 5 is a side elevation of the carriage and trackway in folded condition.

Fig. 6 is a longitudinal sectional view through the hydraulically operated hammer and carriage therefor with the trackways for the hammer in upright position for operation of the apparatus.

Fig. 7 is a diagrammatic view of the hydraulic system for operating the hammer.

Fig. 8 is a partial perspective view illustrating the hydraulic hammer mechanism used for pulling posts.

Fig. 9 is a perspective view of the towing hitch mechanism for the carriage and control for the hammer for operating same during movement of the carriage.

Fig. 10 is a disassembled perspective view of the hammer, adapter head and road patch remover tool.

Fig. 11 is a perspective view of a concrete breaking head for attachment to the hammer.

Fig. 12 is a perspective view of a cutter trim tool adapted to be connected to the hammer adapter head.

Fig. 13 is a scoring chisel adapted to be connected to the adapter head of the hammer.

Fig. 14 is a disassembled perspective view of an extension and tamper tool adapted to be connected to the hammer by the adapter head.

Referring more in detail to the drawings:

1 designates a multipurpose hydraulically operated hammer mechanism and carriage therefor embodying the features of the invention and adapted to be connected to a tractor or other vehicle 2 for towing to locations where work is to be done and also for towing during actual operation of the hammer. The carriage consists of a frame 3 preferably formed of tubing and having a substantially U-shaped member 4, the legs 5 and 6 of which form the side members of the frame, the bridge portion of the U being arcuate and forming one end 7 of the frame with the legs 5 and 6 diverging slightly therefrom. The legs are preferably connected by spaced transverse members 8 and 9, the member 9 preferably being located substantially at the ends of the legs 5

and 6. A pan or other suitable container 10 for tools and the like is mounted on the frame adjacent the end 7 thereof and is additionally supported by a transverse member 11 having its ends secured to the legs 5 and 6. The container 10 also may be used for suitable weights for balancing the apparatus if desired.

Supporting members 12 and 13 are arranged transversely of and secured to the legs 5 and 6, preferably between the container 10 and the cross member 8. An hydraulic pump 14, hydraulic fluid reservoir 15 and prime mover 16 are carried on said supporting members, the prime mover 16 having suitable driving connection 17 with the pump for supplying hydraulic pressure as later described. An axle 18 is preferably secured to brackets 19 extending downwardly from the frame 3 substantially under the transverse member 9, said axle preferably being rigid with the frame. Portions of the axle 18 extend outwardly from the sides of the frame and rotatably mounted thereon are wheels 20 preferably having pneumatic tires 21 thereon for supporting the respective end of the frame 3.

A bracket 22 is rigidly secured to the end 7 of the frame 3 and extends forwardly thereof to mount a portion 23 of a trailer hitch connection with a vehicle such as a tractor, automobile or the like. The bracket 22 includes vertically spaced members 24 and 25 having aligned aperture 26 therein. A shaft 27 extends through the apertures 26 and is rotatably mounted therein, said shaft having a collar 28 engaging the lower spaced member 25 and a transverse hole 29 slightly above the upper spaced member 24 for receiving a cotter pin 20 or the like. A washer 31 is preferably arranged between the cotter pin 20 and the upper spaced member whereby the cotter pin and collar 28 prevent endwise movement of the shaft 27 relative to the bracket 22. A transverse bore 32 is provided adjacent the upper end of the shaft 27 for receiving a bar 33, said bar being held in place by a suitable screw or other clamping means 34.

Fixed on the lower end of the shaft 27 is a bearing sleeve 35 having a bore 36 adapted to rotatably mount a shaft 37 of a yoke 38 which has spaced arms 39 having apertured ends 40 for receiving an axle 41. A wheel 42 is rotatably mounted on the axle 41 and preferably has a pneumatic tire 43 thereon for providing rolling support for the forward end of the frame 3. Fixed to the yoke 38 at each end of the bearing sleeve 35 are arcuate plates 44, said plates being connected at their ends by bars 45 and 46 and also having spaced aligned apertures 47 and 48 for receiving a bolt 49 whereby the bars 45 and 46 and bolt 49 cooperate to fix the yoke in selected angular position relative to the frame 3 for adjusting the height of the front end of the frame when the tire 43 is engaged with the ground or other surface and also for raising the wheel out of engagement with the ground when the apparatus is being towed from one location to another.

Brake shoes 50 are mounted on arms 51 fixed to the ends of a transverse shaft 52 which is rotatably mounted in suitable brackets 53 depending from the frame leg members 5 and 6. Also fixed to the shaft 52 is a lever 54 having suitable means for engaging notches 56 in a segment 57 whereby movement of the lever 54 moves the brake shoes relative to the peripheries of the tires 21 for releasing or engaging the shoes with said tires to hold the carriage in selected location. Brackets 58 and 59 are secured to the transverse

members 8 and 9 substantially on the longitudinal center of the frame 3. Each of said brackets has spaced ears extending upwardly from the transverse members and have aligned apertures for receiving the shanks of bolts 60 or other suitable member adapted to rotatably mount bearing members 61 and 62 on the lower ends of a trackway supporting frame 63 whereby said frame may be oscillated or swung about a longitudinal axis relative to the frame 3.

The trackway supporting frame 63 preferably consists of spaced tubular members 64 and 65 having one end thereof turned downwardly as at 66 and converging to the bearing member 61 which is suitably secured thereto. Brace members 67 have one end secured to the bearing member 62 and their other ends diverging and secured to the frame members 64 and 65 to form a rigid trackway supporting frame. The members 67 are preferably connected intermediate their ends by plates 68 suitably secured thereto and carrying a bolt 69 which extends through a slot 70 in one end of a brace arm 71, the other end of said brace arm being pivotally mounted on ears 72 suitably secured to the transverse member 9 in spaced relation to the bracket 59 whereby the bolt 69 may be tightened to aid in retaining the trackway supporting frame in selected position.

Swinging movement of the trackway supporting frame 63 about the axis through the bearing members 61 and 62 is preferably positively controlled by an arm 73 having one end pivotally mounted as at 74 on an ear 75 carried by the tubular member 65, the other end of said arm preferably being pivotally mounted on trunnions 76 carried by a nut 77 which is threadedly mounted on an adjusting screw 78 rotatably mounted in spaced bearings 79 and 80 on the transverse member 8 whereby said screw 78 is rotatable about an axis transversely of the frame 3. The screw is provided with a crank 81 for rotating said screw and turning of the screw moves the nut 77 transversely of the frame 3 to positively move the trackway supporting frame about the longitudinal axis defined by the bearing members 61 and 62. The ends of the members 64 and 65 are rigidly secured to a yoke member 82 having spaced ears 83 extending rearwardly of the frame. The ears 83 have apertures which align with apertures 84 in pairs of ears 85 for mounting pins 86 to form pivotal connections therebetween. The pairs of ears 85 are rigidly secured to the respective upright members 87 and 88 of a trackway 89 whereby said trackway is carried by the trackway supporting frame 63 and is tilted laterally of the frame 3 when the trackway supporting frame is moved on the longitudinal axis defined by the bearing members 61 and 62 and the aligned pins 86 being on an axis transversely of the frame 3 permit tilting of the trackway longitudinally of said frame as later described.

The upright members 87 and 88 are channel-shaped and are connected at their upper ends by a channel-shaped cross member 90. Cooperating with the cross member 90 to retain the upright members 87 and 88 in proper spaced relation and form a rigid structure are spaced connecting bars 91 and 92, the bar 91 preferably being substantially intermediate the height of the upright member and also spaced above the pairs of ears 85 and the bar 92 is preferably adjacent the lower end of said trackways. Each of the bars 91 and 92 has end portions 93 suitably secured as by weld-

ing to the outer surfaces of the webs of the upright members and the connection portion is ar-
cuate whereby the central portion extends for-
wardly of the upright members and are suitably
spaced therefrom to permit free movement of a
hammer or impact member 94 which is slidably
mounted in the channel-shaped upright members
illustrated in Figs. 2 and 6. The member 94
also preferably has ears 95 extending rearwardly
of the trackway members for connection with a
tow member as later described.

The hammer 94 may be of any desired shape, but is illustrated as having a substantially cylindrical portion 96 having laterally extending side flanges 97 and 98 adapted to slidably engage in the channels 99 and 100 in the upright members 87 and 88. The lower face of the hammer is preferably concaved as at 101 to aid in driving posts without splintering the top of same and also to receive an adapter which may be secured to the hammer as later described.

In order to raise and lower the hammer 94 in the trackways, I preferably provide an hydraulic cylinder 102 having a plunger 103 adapted to be operated by fluid from the pump 14 or other suitable source of fluid pressure. The cylinder is rigidly secured outside the upright member 87 by a bracket 104 adjacent the lower end of said cylinder, the upper end of said cylinder being secured to a lateral extension of the cross member 90 at the top of the trackway. The lower end of the plunger 103 is provided with a sheave or pulley block 105 and spaced pulleys 106 and 107 are rotatably mounted on the cross member 90 to guide a cable 108 operating thereover. One end of the cable 108 is attached to the upper end of the hammer 94 in any suitable manner whereby said cable is adapted to run over the pulley 107, pulley 106, pulley 105 and have its opposite end secured to the bracket 104 or other stationary member. Also the sheave pulleys 105 and 106 may be arranged for a plurality of grooves or separate pulleys whereby the cable may extend over same to provide additional strands therebetween to increase the mechanical advantage of the arrangement.

Hydraulic fluid for operating the plunger 103 is provided by the pump 14 which preferably has a pressure responsive bypass built therein. A fluid line 109 leads from the pump to a valve 110 provided with an actuating lever 111. A fluid line 112 connects between the control valve 110 and the upper end of the cylinder 102 for supply of fluid back of the plunger 103 for actuating same. A return line 113 is connected between the control valve 110 and the fluid supply reservoir 15. The control valve 110 has three positions, one to raise the hammer, one to lower the hammer and the central or hold position. Raising and lowering of the hammer is manipulated through operation of the control valve lever 111. When the hammer is raised through operation of the lever, the return of the lever to lowered position will open a port on the return side of the valve and the return lines are of a diameter to allow the hammer to drop substantially freely without back pressure or restriction from the fluid in the cylinder. The ratio of travel between the plunger and hammer is such that it will allow the hammer to travel the full length of the guide from the cross member 90 to the ground. The length of the stroke of the hammer may be regulated by the control valve and also the hammer may be stopped as desired in selected vertical position.

6
by moving the lever 111 to the neutral or hold position.

The trackways 89 may be tilted fore and aft or longitudinally of the carriage by moving said trackways about the axis of the pins 86. The trackways are moved and also held in selected position by means of an adjustable, foldable brace 115. The brace 115 consists of a link 116 having one end pivoted on a pin 117 carried by ears 118 fixed to the connecting bar 91. The other end of the link 116 is pivotally mounted on a pin 119 carried by spaced arms 120 intermediate the ends thereof. The adjacent ends of the arms 120 are provided with apertures 121 adapted to align with an aperture 122 in the link 116 when the link and arms are in alignment for receiving a bolt 123 for retaining the link and arms as a stiff brace member. The arms 120 preferably are provided with a stop 124 adapted to be engaged by the link 116 when in alignment with the arms 120 whereby the link and arms may be pivoted on the pin 119 in one direction only for folding the brace 115. The opposite end of the arms 120 are fixed to a nut 125 having a threaded bore adapted to receive a threaded shank 127 of an adjusting screw 128. The screw 128 is rotatably mounted and fixed against longitudinal movement in a bearing member 129 having trunnions 130 rotatably mounted in a bracket 131 fixed to the members 64 and 65 adjacent the bend thereof. The adjusting screw is provided with a crank member 132 to facilitate turning of the screw. With this arrangement, turning of the crank 132 screws the shank 127 into or out of the nut 125 to lengthen or shorten the brace 115 and when the link 116 and arms 120 are held in alignment, as illustrated in Fig. 6, the turning of the crank 132 will tilt the trackway fore or aft of the carriage.

When it is desired to position the trackways as illustrated in Fig. 5 for transportation, the hammer 94 is preferably positioned relative to the pins 88 for the most advantageous position for lowering the trackways. The crank 132 is then turned to tilt the trackway whereby the top thereof moves toward the front of the carriage. The bolt 123 is then removed from the apertures 121 and 122 whereby the link 116 and the arms 120 may be relatively pivoted on the pin 119 as illustrated in Fig. 4. The top of the trackways are then pulled over toward the front of the carriage to the position shown in Fig. 5, whereby a stop member 133 on the bar 91 engages a plate 134 on the frame member 64. Suitable fastening devices 135 may be applied to the stop and plate for retaining the trackways in folded position during the transportation. Also suitable apertures may be arranged in the flanges of the upright members 87 and 88 for receiving bolts 137 said bolts being spaced whereby they substantially engage the ends of the flanges 97 and 98 to retain the hammer against movement in the trackways during transportation.

A foot member 138 has a leg 139 slidably mounted in guides 140 secured to the outer face of the upright member 87. Spaced plates 141 are secured on the upright member 87 on opposite sides of the leg 139, said plates having a plurality of apertures 142 for receiving a pin 143 adapted to engage lugs 144 on the leg 139 to selectively anchor the foot member relative to the upright member with the foot member engaging the ground to provide support to the trackways. Arranged on the pulley block 105 is a clevis 145 to which a chain 146 may be attached.

In pulling posts or the like, the foot member 138 is secured to the upright member 81 with said foot member engaging the ground. The chain 146 is then wrapped or otherwise secured to a post 147 to be pulled and said chain connected to the clevis 145, when the plunger 103 is in partially extended position. Then by manipulation of the valve 111 to drop the hammer and the dropping of said hammer will provide a jerking force when the chain 146 becomes taut to loosen the post and then the gravity acting on the hammer or additional dropping of the hammer will tend to apply sufficient force to the chain through the cables and pulley blocks to pull the post from the ground.

When used for repairing or maintaining highways and right of ways, it is desirable to use different attachments to the hammer 94 depending upon the particular work to be done. In order to apply the attachments to the hammer, said hammer is provided with bosses 148 adjacent the lower end thereof, said bosses having apertures 149 adapted to align with apertures 150 in bosses 151 of an adapter head 152 whereby bolts 153 will extend through the apertures 149 and 150 and be engaged by nuts 154 to secure the adapter head on the bottom of the hammer 94. The adapter head is provided with an axial aperture 155 for receiving the shank 156 of various tools to be used on the hammer. The shank of each tool is provided with a groove 157 adjacent the side thereof for alignment with a transverse bore 158 in the adapter head for receiving a pin 159 to key the shank 156 of the respective tool in the adapter head.

The tool 160 illustrated in Fig. 10 is a patch removing tool which has a plate 161 adapted to engage the lower end of the adapter head and depending from the plate is a pointed member 162 which is particularly adapted for removing a patch from a hard surface road. A cutter trim tool 163 is illustrated in Fig. 12, said tool having a shank 156 with a groove 157 therein and is provided with a surface 164 surrounding the shank and adapted to engage the lower surface of the adapter head 152. The particular tool is semicircular in shape with a peripheral edge 165 adapted to cut or otherwise trim places being repaired in roads. A chisel 166 is illustrated in Fig. 13, said chisel having a shank 156 with a groove 157 therein which is similar to the shank of the tool illustrated in Fig. 10. Said chisel also has a surface 167 adapted to engage the bottom of the adapter head 152 and is provided with a sharpened lower end 168 to score or otherwise mark pavement or the like in the repairing operation.

A tamping tool 169 is illustrated on the hammer in Fig. 3 and also in disassembled relation in Fig. 14. The tamping tool preferably is provided with a suitable extension 170 whereby it may be used in trenches and the like to tamp the ground without the hammer dropping from the trackways. The extension 170 is preferably a cylindrical shaft of suitable size to be received in the aperture 155 of the adapter head and also in an aperture 171 in the tamping head 172. Grooves 173 are provided adjacent each end of the extension 170 to align with the aperture 158 in the adapter head 152 and with an aperture 174 in the tamping head 172 whereby pins 159 and 175 may be inserted in said apertures and engage in the grooves to retain the extension in the adapter head and tamper head respectively. In order to transmit the force from the

hammer and adapter head to the tamper head a tubular member 176 is sleeved over the extension 170, said tubular member having end plates 177 and 178 adapted to engage the lower face of the adapter head 152 and the upper face of the tamping head.

A paving breaker 179 is illustrated in Fig. 11, said breaker being adapted for direct connection to the lower end of the hammer 94 and is provided with bosses 180 having apertures 181 adapted to receive bolts for securing the paving breaker to the hammer. The lower surface of the paving breaker is preferably arcuate or ball-shaped but may be otherwise shaped to satisfactorily break the pavement.

In using various tools on the hammer, it is sometimes preferable to continuously move the hammer and carriage therefor along the line of operation of the hammer and to provide control of the operation of the hammer from the seat of the towing vehicle, for example the tractor 2. In such operations a hitch 182 is connected to the carriage and trackways. The hitch preferably consists of a U-shaped member 183 having ends suitably secured to arms 184 on the transverse member 9, said U-shaped member being provided with a clevis 185 adapted to be connected to the draw bar or the like of the tractor 2. The U-shaped member is braced by members 186 having one end connected to ears 187 on the U-shaped member and having the other end provided with a plurality of spaced apertures 188 adapted to be suitably connected to the ears 95 on the trackways 89. With this arrangement, an extension 189 is applied to the valve member and connected to one end of a lever 190 suitably pivoted on a bracket 191 which is secured to one of the members 186 whereby the lever 190 is adjacent the side of the seat of the tractor 2. Then by operation of the tractor to draw the carriage and manipulation of the lever 190 the hammer 94 may be raised and dropped whereby the tool on the lower end of the hammer will break pavement or otherwise perform desired functions in the repair and maintenance of roads and highways.

In operation of an apparatus constructed as described, and assuming same is in the position as shown in Fig. 5, the bar 33 is inserted in the socket fixed on the yoke member 38 and the bolt 49 removed from its apertures whereby upward pull on the bar will swing the wheel 42 downwardly relative to the frame 3, lifting the hitch portion 23 whereby it may be attached to the hitch connection on an automobile or tractor. The wheel 42 is then swung back upwardly to the position shown in Fig. 5, and the bolt 49 inserted to retain same in position. The apparatus is then moved to the location of work to be done. Again by use of the rod 33 and after removal of the bolt 49, the wheel may be swung downwardly to lift the hitch from the hitch connection on said towing vehicle and then the wheel is moved to a position to give the proper elevation of the front end of the frame 3 and the bolt 49 inserted to the proper aperture to retain the wheel in ground engagement and the frame in proper position. The fastening device 135 is then removed from the stop member 133 and plate 134, and by applying force to the upper end of the trackway it is pivoted upwardly on the pins 86, moving the link 116 into alignment with the arms 120. When in alignment, the bolt 123 is inserted into the apertures 121 and 122 to retain

the link and arms in alignment. By rotating the crank 132 to screw the shank 127 in the nut 125, the trackways are tilted fore and aft as desired. By rotating the crank 84 to turn the screw 78 in the nut 77, the trackway supporting frame 63 is moved to provide proper side tilt or position the trackways 89 as desired.

The engine 16 is then started to operate the pump 14 to provide the hydraulic fluid pressure to the valve 110. The bolts are removed from the apertures in the flanges of the trackway to free the hammer 94 for operation. Then by manipulation of the lever 111 to operate the valve 110, the hammer may be raised upwardly as desired, and by release of the fluid in the cylinder 102 the hammer will drop freely. The desired tools may be applied to the lower end of the hammer for performing the work necessary. Also the hitch 182 may be attached to a tractor or the like whereby the carriage may be towed while the hammer is being operated to perform the desired work.

It is believed obvious I have provided a multi-purpose hydraulically operated hammer and carriage therefor in such a structure that can be operated by one man to provide smashing blows or light blows as desired on flat and sloping terrain.

What I claim and desire to secure by Letters Patent is:

1. A portable drop hammer comprising, a carriage, a frame pivotally mounted on the carriage and swingable about an axis longitudinally of said carriage, means adjustably connecting the frame and carriage for controlling pivotal movement of the frame, a trackway, means pivotally mounting the trackway on the frame for swinging movement about an axis transversely of the carriage, hingedly connected brace members one of which is pivotally mounted on the frame and the other having pivotal connection with the trackway above the pivotal mounting thereof, removable means connecting the brace members to hold same against hinging movement, one of said brace members being adjustable in length for adjustably tilting the trackway fore and aft of the carriage, said brace members having relative hinging movement upon removal of said connecting means to permit pivoting the trackway on its mounting means for folding said trackway downwardly over the carriage, a hammer having sides sliding in said trackway, a source of fluid pressure, and means selectively operated by said fluid pressure for raising the hammer in the trackways, said means upon release of the fluid pressure permitting substantially free falling of the hammer.

2. A portable drop hammer comprising, a carriage having ground engaging wheels for supporting same, a frame pivotally mounted adjacent one end of the carriage and swingable about an axis longitudinally of said carriage, means adjustably connecting the frame and carriage for controlling pivotal movement of the frame, a trackway, means pivotally mounting the trackway on the frame for swinging movement about an axis transversely of the carriage, a brace arm adjustable in length and pivotally mounted on the frame, a link having spaced pivotal connections with the brace arm and with the trackway above the pivotal mounting thereof, removable means connecting the link and brace arm in spaced relation to the pivotal connection therefor for holding same in alignment for adjustably tilting the trackway fore and

aft of the carriage upon adjustment of the length of the brace arm, said brace arm and link having relative pivotal movement upon removal of said removable connecting means to permit pivoting the trackway on its mounting means for folding said trackway downwardly over the carriage, a hammer having sides sliding in said trackway, a source of fluid pressure on the carriage, and means selectively operated by said fluid pressure for raising the hammer in the trackways, said means upon release of the fluid pressure permitting substantially free falling of the hammer.

3. A portable drop hammer comprising, a carriage having ground engaging wheels for supporting same, a frame pivotally mounted adjacent one end of the carriage and swingable about an axis longitudinally of said carriage, means adjustably connecting the frame and carriage in spaced relation to the pivotal mounting of said frame for controlling pivotal movement of the frame, a trackway, means pivotally mounting the trackway on the frame for swinging movement about an axis transversely of the carriage, hingedly connected brace members one of which is pivotally mounted on the frame and the other having pivotal connection with the trackway above the pivotal mounting thereof, removable means connecting the brace member to hold same against hinging movement, one of said brace members being adjustable in length for adjustably tilting the trackway fore and aft of the carriage, said brace members having relative hinging movement upon removal of the connecting means therefor to permit pivoting the trackway on its mounting means for folding said trackway downwardly over the carriage, a hammer having sides sliding in said trackway, a cylinder and piston one of which is fixed relative to the trackway, means connecting the other to the hammer whereby relative movement of the cylinder and piston moves the hammer in the trackway, a source of fluid pressure, and means selectively operated to supply said fluid pressure to the cylinder to effect relative movement of the piston therein for raising the hammer in the trackways, said means being operable to release the fluid pressure in the cylinder and permit substantially free falling of the hammer.

4. A portable drop hammer comprising, a frame, ground engaging means on the frame for supporting same, a second frame pivotally mounted on the first named frame and swingable about an axis longitudinally of said first named frame, a screw and link assembly adjustably connecting the second frame and first named frame in spaced relation to the pivotal mounting thereof for effecting pivotal movement of said second frame, spaced parallel members forming a trackway, said spaced members having channels forming guides in said trackway, means pivotally mounting the trackway on the second frame, a screw and link assembly one of which is pivotally mounted on the second frame and the other having pivotal connection with the trackway above the pivotal mounting thereof, said screw and link assembly being adjustable in length for adjustably tilting said trackway fore and aft of the first named frame, a joint in the screw and link assembly for selective relative folding thereof whereby said trackway may be pivoted on its pivotal mounting for folding over the first named frame, an impact member having sides sliding in the trackway guides, a pump on the first named frame, power means

11

for driving said pump to provide fluid pressure, a cylinder rigidly secured to the trackway, a piston in the cylinder and extending therefrom, pulleys on the end of the piston and on the upper end of the trackway, a cable having one end attached to the trackway adapted to engage and run over said pulleys and having its opposite end attached to the impact member, means for supplying fluid pressure to the cylinder whereby said piston is extended therefrom to raise said impact member, and means for releasing the fluid from the cylinder for dropping said impact member.

5. A portable drop hammer comprising, a frame, ground engaging wheels on the frame for supporting same, a second frame pivotally mounted on the first named frame and swingable about an axis longitudinally of said first named frame, said second named frame extending upwardly from the axis of pivotal movement thereof, a screw and link assembly adjustably connecting the second frame and first named frame in spaced relation to the pivotal mounting thereof for effecting pivotal movement of said second frame, spaced parallel members forming a trackway, said spaced members having channels forming guides in said trackway, means pivotally mounting the trackway on the second frame above the pivotal mounting thereof, a brace means including two hingedly connected members one of which is pivotally mounted on the second frame and the other having pivotal connection with the trackway above the pivotal mounting thereof one of said hingedly connected members being adjustable in length for adjustably tilting said trackway fore and aft of the first named frame, removable means connecting the frame members in spaced relation to the hinge connection when said brace members are 30 35 40 in alignment to form a stiff brace whereby re-

moval of said removable means permits relative hinging of the brace members and pivotal movement of the trackway on its pivotal mounting for folding said trackway over the first named frame, an impact member having sides sliding in the trackway guides, a pump on the first named frame, power means for driving said pump to provide fluid pressure, a cylinder rigidly secured to the trackway, a piston in the cylinder and extending therefrom, pulleys on the end of the piston and on the upper end of the trackway, a cable having one end attached to the trackway adapted to engage and run over said pulleys and having its opposite end attached to the impact member, means connecting the pump to the cylinder for applying fluid pressure thereto for raising the impact member in the trackway, and valve means between the pump and cylinder for controlling application of fluid pressure thereto, said valve means and cylinder having a relatively large exhaust connection whereby operation of the valve means releases the fluid pressure to allow the impact members to drop substantially freely in the trackway guides.

EVAN E. DORKINS.
